PNEUMATIC TOOL

John Arthur, Camborne, England

Application August 5, 1942, Serial No. 453,653
In Great Britain December 11, 1941

2 Claims. (Cl. 121—19)

This invention relates to pneumatic and like tools and has reference particularly to riveting and chipping hammers of the general kind having a free piston whose movement is controlled by a valve mechanism comprising a main oscillating distributing valve and an auxiliary oscillating controlling valve; the arrangement being such that compressed air or other elastic fluid, hereinafter referred to as "compressed air," is alternately admitted from a source of supply alternately to the two ends of the cylinder in which the free piston reciprocates.

The invention is more particularly related to tools of this kind as described in U. S. Patent No. 1,969,539, and it has for its object to simplify and improve the valve mechanism so as to reduce the numbers of angled passages and thus secure entry of the air into the working cylinder, at a higher velocity, with the result that higher piston speeds are attained with a lower air consumption.

The invention consists broadly of a pneumatic pressure tool of the foregoing character having an annular disc main valve so arranged that the compressed air from the source of supply passes directly in the radially inward direction into the end of the cylinder across the valve face to effect the forward movement of the piston.

In order that the invention may be readily understood reference is now made to the accompanying drawing, wherein:

Figure 1 is a longitudinal section of the main portion of the complete tool, with the valve mechanism and piston shown in elevation, and in the positions which they occupy at the commencement of the operative movement of the piston.

Figure 2 is a sectional view to an enlarged scale of the valve end of the tool, same being taken on line II—II of Figure 3 with the valve elements shown in section.

Figure 3 is a cross-section on the line III—III of Figure 2.

Figure 4 is a view similar in all respects to Figure 2, taken on line IV—IV of Figure 5, but with the valve elements in the position they occupy to effect the return stroke of the piston, and

Figure 5 is a cross-section on the line V—V of Figure 4.

Referring to the drawing, and adopting as far as practicable the nomenclature used in the specification of Patent No. 1,969,539, the numeral 1 designates the main distributing valve, 2 is the auxiliary valve, 3 is the freely moving piston, 4 is the cylinder, 5 is the valve box, 6 is the cylinder cover, which fits in an enlargement of the cylin-

der end, 7 is the valve box cover, and 8 is the handle of the tool, which is screwed on to the cylinder end and maintains the whole assembly positioned.

With the parts in the positions shown in Figures 1 and 2, the piston 3 being at the upper end of the stroke, air enters through the passage 9 in the handle, and filling the space 10 within cover 8, passes directly into the cylinder 4 through ports 11 in the wall of the valve box 5, across the face of the disc 1a of the valve 1 and the adjacent face of the valve box cover 7. Air under pressure also passes through ports 12 to the passages 13 beneath the valve disc 1a, and by way of the passages 14, 15 and 16 to the annular space 17 at the back of the skirt 1b of the valve 1. By reason of the greater area of the disc 1a the valve 1 is maintained in the position shown, so that the compressed air can pass freely into the cylinder across the valve face 1a as above stated.

The piston 3 thereupon moves along the cylinder 4 and until it reaches the port 18, the air in front of the piston can escape freely to atmosphere through port 18 and passage 19. On the piston reaching and closing port 18, thus preventing exhaust to atmosphere, compression in the front end of the cylinder during continued movement of piston 3 is prevented by the action of the auxiliary valve 2 as hereinafter explained.

When the piston passes port 18 it drives air through port 26, passage 25 and port 24 into arcuate grooves 28 milled in the cylinder cover 6, which lie below the auxiliary valve 2. The valve 2 is consequently raised to create an annular space between it and the flange of the cylinder cover 6 on which it rests, as shown in Figure 2, which allows the air to exhaust through ports 23 and passage 19.

Also, when the piston 3 passes the port 18, the upper end of the cylinder is connected to atmosphere through passage 19. The sudden escape of air causes a pressure drop on valve face 1a, so that the forward pressure on the valve 1 is overcome by the rearward pressure on the end of the skirt 1b in annular space 17 added to the pressure in passages 13. Consequently, the valve 1 moves rearwardly into the position shown in Figure 4, in which the valve flange 1a is pressed against valve box cover 7, so that the supply of air to the cylinder 4 behind the piston 3 is shut off by valve 1. At the same time a space is created round the valve 1 beneath the flange 1a, and the uncovering of ports 13 and 20 permits air to pass from ports 13 to ports 20, and thence through passages 21 into the annular groove 22 behind the

auxiliary valve 2. The area of this groove 22 is greater than the combined areas of the arcuate grooves 28.

The auxiliary valve 2 is therefore forced from the position shown in Figure 2 to that shown in Figure 4, in which it closes the port 23 communicating with the atmosphere through passage 19. At the same time air from groove 22 passes through holes 33 in the auxiliary valve 2 into the arcuate grooves or slots 28, whence it passes through passage 24 along passage 25 in the cylinder wall to the front end of the cylinder via port 26. The piston 3 is in consequence driven in the reverse direction on its return stroke.

In performing its return stroke the piston closes port 18 and then compresses the air trapped in the cavity 21 of the valve box cover 1, until at the end of the stroke the pressure has risen sufficiently for the pressure on the edge of valve face 1a projecting beyond the edge of the cavity 21 (the internal diameter of the valve being slightly less than the diameter of the cavity 21) to overcome the pressure on the valve skirt 1b in annular space 17, added to the pressure on the underside of the valve flange 1a, the pressure below the valve flange 1a having in the meantime been reduced by the connection of the forward cylinder space to atmosphere through port 18 and passage 19, said cylinder space being connected to the space below valve annulus 1a through ports 20, passages 21, valve holes 33, arcuate grooves 28, passages 24, 25 and port 26.

The valve 1 is consequently forced back into the position shown in Figure 2 ready for repetition of the operating cycle.

I claim:

1. A pneumatic percussive tool comprising a hollow substantially cylindrical casing, a reciprocating hammer slidable in said casing, a cylindrical valve guide fitted into a recess at the rear end of said casing, said guide having an axially ported radial flange at the end thereof seated in said recess with its opposite end projecting from said recess, an annular disc valve having a sleeve portion slidable on the projecting end of said valve guide, an axially and radially ported sleeve encircling said valve guide between its radial flange and the valve disc, which seats in a recess in said sleeve, and having a radially ported skirt portion extending rearwardly beyond the valve disc, said axially and radially ported sleeve having passages therein providing communication between its end faces and being recessed to fit over the valve sleeve, a false inner cover member fitted into said skirt portion and having an annular projection approaching the rear face of the valve disc and annularly spaced from said skirt portion to form a cavity which encircles said annular projection and the rear part of the valve disc, and an outer cover member for said casing adapted to enclose the aforesaid parts, said outer cover member having an inlet connection for the compressed air for operating the tool, which communicates with its interior space surrounding said ported sleeve and its skirt.
2. A tool according to claim 1, wherein said axially and radially ported sleeve has internally communicating ports opening axially at its rear end adjacent the valve disc and radially through the outer wall of said sleeve into the interior of said outer cover member.

JOHN ARTHUR.
